WINDOW CONSTRUCTION

Harry Jakush, Chicago, Ill.

Application June 14, 1957, Serial No. 665,722

10 Claims. (Cl. 20—42)

Fig. 4 is a cross sectional view on a vertical plane, taken on line 4—4 of Fig. 3, illustrating the position of the window sashes when the same are angularly shifted within a dwelling;

5 Fig. 5 is an enlarged elevational view, partly in section, taken substantially on the same plane as shown in Fig. 4, illustrating the closed position of the upper sash, with the mechanism for vertically sliding the same within a window frame, and with the mechanism for angularly shifting the upper sash within a dwelling;

10 Fig. 6 is an enlarged cross sectional view, showing a fragment of the mechanism illustrated in Fig. 3;

15 Fig. 7 is an edge elevational view of the two window sashes, illustrating the position of the lower sash when shifted inwardly of the dwelling to a plane removed from the plane of the upper sash, further illustrating the mechanism whereby the lower window sash may be shifted to the position stated as well as to the angular position thereof;

20 Fig. 8 is a similar view as that shown in Fig. 7 of the lower window sash, illustrating the angular position of the lower window sash with the mechanism for supporting said window sash in that position;

25 Fig. 9 is a fragmentary face elevational view of the lower window sash with the mechanism whereby the said window sash may be shifted and supported in its positions shown in Figs. 7 and 8, the view having been taken substantially upon a plane indicated by line 9—9 of Fig. 7; and

30 Fig. 10 is a perspective view of a portion of the mechanism whereby the lower window sash may be shifted to the various positions above indicated and illustrated in Figs. 4, 7 and 8, and whereby the same may be maintained in those positions.

35 Referring in detail to the present drawings there is shown therein a window frame which includes vertical frame side members 11, lower horizontal frame member 12 and upper horizontal frame member 13. Inner window sill 14 is rigidly supported upon said lower horizontal frame member 12. Rigidly supported on the underface of said upper horizontal frame member 13 is board 15 (Fig. 2), which may be optionally used in connection with said upper horizontal frame member 13. Adjacent its outer edge said board 15 is provided with recess 16 for the purposes hereinafter specified. Outwardly of the window frame vertical frame bars 17 are rigidly connected with the outer edges of said vertical frame members 11. Vertical molding strips 18 are affixed to the inner edges of said frame bars 17. Affixed to the inner faces of said vertical frame side members 11 are molding strips 19, which are in a spaced relation with the oppositely disposed inner faces of said frame bars 17. Affixed to the inner face of each of said molding strips 19 is weather strip 20, including an inwardly directed extension 21.

40 Fitted within the window frame as hereinabove defined is a lower window sash, which includes a lower horizontal sash bar 22, upper horizontal sash bar 23 and a pair of vertical sash bars 24, said bars being arranged in a frame for maintaining therewithin window pane 25.

45 The upper window sash includes a lower horizontal sash bar 26, an upper horizontal sash bar 27 and a pair of vertical sash bars 28, said bars being arranged in a frame for maintaining therewithin window pane 29.

50 The upper horizontal bar 23 of the lower sash and the lower horizontal bar 26 of the upper sash are suitably molded to define scarf joint 30, so formed however that when the two sashes are in a mutually closed relation within the window frame, as seen in Fig. 2, the upper window sash cannot be moved either vertically or angularly until the lower sash by its upper portion has

The present invention relates to window construction and has for its main object the provision of means whereby two window sashes may remain upon the same vertical plane when the sashes are in a closed mutual relation as well as in a closed relation with the window frame, unlike in the conventional window sashes which are slidable within a window frame on two different planes.

Another object of the present invention is the provision of a suitable mechanism whereby the two window sashes may be angularly shifted within a dwelling for providing ventilation, and whereby the two window sashes may be brought to a horizontal position to permit access to the outer faces of the window panes for cleaning or washing the same.

Still another object of the present invention is the provision of a suitable mechanism whereby one of the window sashes may be bodily shifted inwardly of the dwelling and brought within a plane removed from the plane of the other window sash, and whereby the first of said window sashes may be shifted in a vertical direction upon the plane which is removed from the plane of the other window sash.

Still another object of the present invention is the provision of means whereby a window sash, when angularly shifted out of a window opening, may be maintained in its angular adjusted position.

A still further object of the present invention is the provision of novel means for guiding the upright shifting movement of a window sash bodily within a window opening, irrespective as to whether the window sash has been angularly shifted within a dwelling or whether the same is in its normal closed position within a window opening.

A still further object of the present invention is to generally improve a window construction, including a window frame and a window sash of the type capable of angular adjustment within the window frame and capable of upright shifting movement within the window frame either during its normal closed position or its angular adjusted position.

With the above general objects in view and others that will appear as the invention is better understood, the same consists in the novel construction, combination and arrangement of parts hereinafter more fully described, illustrated in the accompanying drawings and pointed out in the appended claims.

In the drawings forming a part of this application and in which like designating characters refer to corresponding parts throughout the several views;

Fig. 1 is a plan elevational view of the window frame and the two window sashes when in a closed position, looking at the face side thereof inwardly of the dwelling;

Fig. 2 is a cross sectional view taken on line 2—2 of Fig. 1;

Fig. 3 is a horizontal cross sectional view taken on line 3—3 of Fig. 1;

been angularly shifted within a dwelling. It is noted that the two window sashes when in a closed position within the window frame remain on the same vertical plane as is clearly seen in Fig. 2.

Felt weather strip 31 is affixed to the inwardly disposed face of each molding strip 18 and is interposed therebetween the vertical sash bars 24 and 28 of the two window sashes, as best seen in Figs. 3 and 6, for preventing dust and wind from entering the dwelling when the two sashes remain in a closed position within the window frame.

Carried upon the inner face of each vertical sash bar 24 and 28 of the two window sashes is molding strip plate 32, which by its inner free edge, which defines lip 33, overlaps and engages extension 21 of said weather strip 20, as is best seen in Fig. 6. Thus, when the two window sashes are in a closed position within the window frame, extension 21 and lip 33 are in a mutually contacting relation for providing a seal for preventing dust or wind from entering a dwelling.

It is further observed that when the two sashes are in a mutual vertical alinement, as seen in Fig. 2, the lower horizontal bar 22 of the lower window sash remains in contact with the outer edge of the window sill 14, while the upper horizontal bar 27 of the upper sash remains within recess 16 of board 15.

Each of the vertical sash bars 24 and 28 of the two window sashes remain spaced from each vertical frame side member 11, as best seen in Fig. 6, and in conjunction with frame bars 17 and molding strips 19 define oblong vertical housings 34, one adjacent each of said vertical frame side members 11, extending along the entire height of the window frame, as best seen in Figs. 3 and 6.

Positioned within each housing 34 and rigidly secured by their ends to the lower and upper horizontal frame members 12 and 13, is a pair of rods 35. With relation to the inside of the dwelling a pair of opposed rods 35 which are farthest removed from the dwelling, or more specifically those which are nearest to frame bars 17, will be hereinafter referred to as outer rods 35, while a pair of opposed rods 35 which are nearest to the dwelling, or more specifically those which are adjacent molding strips 19, will be hereinafter referred to as the inner rods 35.

Affixed to each of the side edges of the vertical sash bars 28 of the upper window sash, by means of a plurality of screws 36, and adjacent the lower end thereof, is plate 37.

Positioned upon each of said outer rods 35 for upright sliding thereon is a lower sleeve 38 and an upper sleeve 39. Extending from the lower end of the lower sleeve 38, in the direction of each of said vertical sash bars 28, is pin 40 which enters an aperture provided in the lower end of each plate 37, and thereby forms a pivot for the lowermost end of the upper window sash, upon which the latter may angularly swing as is seen in Fig. 4. As an alternative construction of the said pivot, shown in Fig. 5, rod 41 is made to extend through the entire length of the lower horizontal sash bar 26 and through the two plates 37, and enter, by its ends an enlargement 42 made at the lower end of each sleeve 38, and thereby form a pivot upon which the upper window sash may angularly swing inwardly of the dwelling, as shown in Fig. 4.

Coating with each side of the upper window sash is arm 43, which by its lower end is pivotally affixed, as at 44, to plate 37, at a point substantially centrally of the latter, and by its upper end is pivotally connected, as at 45, to sleeve 39, adjacent the lower end thereof.

Assuming that the lower window sash is angularly shifted out of the window opening and is otherwise out of the path of the upper window sash, the conditions which will be later apparent, the upper window sash is capable of angularly shifting within the dwelling from the window opening and of assuming various angular positions from almost vertical position to the horizontal position, the latter best shown in Fig. 4. When in that latter position

the outer face of the window pane 29 will become exposed within the dwelling thereby permitting ready access thereto for the purpose of washing the same. One of the intermediate positions of the upper window sash between vertical and horizontal is indicated by dotted lines in Fig. 4. When in one of said intermediate positions the opening of the window will provide ventilation.

Regardless as to what extent the upper window sash is angularly shifted from within the window opening the former moves upon its pivot 40 or 41. When the upper window sash remains in a horizontal position arm 43 shifts to an angular position both with relation to the upper sash and to the upper sleeve 39 as is seen in Fig. 4. Since said upper sleeve 39 is capable of shifting upon each of outer rods 35 to or away from the lower sleeve 38, the two sleeves remain in a spaced mutual relation, as is seen in Fig. 5, with arm 43 remaining in a vertical position when the upper window sash is within the window opening. When however the upper window sash has been angularly shifted to the horizontal position, shown in Fig. 4, upper sleeve 39 by its lower end comes in contact with the upper end of lower sleeve 38, and the latter acts as a stop for preventing farther angular shifting of the upper window sash beyond the horizontal plane.

When the lower window sash has been angularly shifted it is possible for the upper window sash to shift downwardly and within the confines of the lower portion of the window opening, the outer rods 35 guiding sleeves 38 and 39 in their shifting movement.

Referring to the mechanism for angularly shifting the lower window sash within the window opening, positions best shown in Figs. 4 and 8, as well as for bodily moving the lower window sash away from the plane of the upper window sash, position best shown in Fig. 7, the same includes a pair of lower sleeves 46 and a pair of upper sleeves 47 positioned for upright sliding movement upon inner rods 35.

An L-shaped member, generally indicated by 48 in Fig. 10, fitted upon each of the two lower edge corners of the lower sash, includes side plate 49, affixed by a plurality of screws 50 to each side edge of vertical sash bars 24, and bottom plate 51 affixed to each end of the lower edge of the lower horizontal sash bar 22 by means of screws which pass through apertures 52. The lower end of plate 49 has an extension 53 directed toward a dwelling, with an arculate recess 54, opening upon the outer edge of said plate 49 and entering said extension 53.

The ends of the lower horizontal sash bar 22 are filed away from the continuing side edges of the vertical sash bars 24, for defining, in conjunction with the lower end of each plate 49 a recess 55, for accommodating therewithin link 56, which by its upper end is pivoted upon pin 57 mounted upon plate 49 and extending inwardly of recess 55 adjacent the upper end of the latter.

Each of said lower sleeves 46, adjacent its lower end, is provided with a rigidly affixed pin 58, which extends toward the lower window sash, in a transverse relation with and past said plate 49.

Coating with each side edge of the lower window sash is arm 59, which by its lower end is pivoted to the outer face of plate 49, substantially centrally thereof, by means of pin 60. By its upper end said arm 59 is pivoted to the lower end of the upper sleeve 47, upon pin 61.

When the lower window sash remains within the window opening or when the same is angularly shifted, in either of those cases pin 58 remains within the closed end of recess or slot 54, pins 58 constituting the supporting pivot or fulcrum for the sash while in those positions, as seen in Figs. 4 and 8. When the lower window sash has been shifted to the horizontal position, as seen in Fig. 4, lower ends of upper sleeves 47 coming in contact with the upper ends of lower sleeves 46, prevent further downward shifting movement of the lower window sash beyond the horizontal plane. When the lower window sash is shifted angularly from horizontal towards the

window opening, then arms 59 shift the upper sleeves 47 away from the lower sleeves 46, as is seen in Fig. 8. When the lower window sash is within the window opening in closed position, arms 59 remain in a vertical position and in parallelism with inner rods 35, sleeves 46 and 47, and vertical sash bars 24. Similarly as was already described in connection with the upper window sash, when the lower window sash is brought to its horizontal shifted position, shown in Fig. 4, the outer face of the window pane 25 will be exposed within the dwelling permitting access thereto for the purpose of washing or cleaning. The lower window sash is capable of assuming various angular positions from vertical closed position to the horizontal position, as is seen in Figs. 4 and 8. No matter what particular angular position, from the vertical closed position, the lower window sash assumes, it is capable of bodily shifting in a vertical direction as is clearly indicated in Figs. 4 and 8, being guided in its bodily vertical shifting movement by the inner pair of rods 35 and sleeves 46 and 47.

Arms 59 support the lower window sash in its angular adjusted position.

It is also noted that when the lower window sash is in a horizontal position pin 58 does not extend to the closed end of recess 54, but remains substantially centrally thereof, as is seen in Fig. 4. It is also noted that when the lower window sash is in a closed position within the window opening, the same is pushed in the direction away from the dwelling, until said lower window sash is on a common plane with the upper window sash, with the lower horizontal sash bar 26 of the upper window sash interconnected with the upper horizontal sash bar 23 of the lower window sash, through joint 30, as is seen in Fig. 2. In that closed position of the lower window sash pins 58 will find themselves within the closed ends of slots 54, as is seen on reference to the showing in Fig. 8. In that closed position of the lower window sash within the window opening arms 59 will not be on a vertical line, but their lower ends will be on a plane toward the outside of the dwelling, with the upper ends of said arms 59 on a plane nearer to the dwelling, position substantially opposite from that shown in Fig. 7.

To bodily shift the lower window sash to the plane away from that of the upper window sash, first the upper end of the lower window sash is shifted within the dwelling, for bringing the lower window sash to an angular position. Thereupon the lower window sash while in that angular position is bodily shifted in an upward direction until the lower horizontal sash bar 22 clears sill 14. When this has been accomplished the lower end of the lower sash is shifted inwardly of the dwelling. This latter operation causes link 56 to angularly shift and assume the position out of recess 55, as is seen in Fig. 7. Bodily shifting of the lower portion of the lower window sash moves the lower end of the lower window sash away from pins 58 so that said pins 58 remain out of slots 54, as is seen in Fig. 7.

When the above several steps have taken place the lower window sash will be moved out of the plane of the upper window sash, with the lower window sash bodily shifted within the dwelling, as is seen in Fig. 7, ready to be shifted in an upward direction to assume an aligned position on a horizontal plane with the upper window sash, thereby completely clearing the lower portion of the window opening.

Obviously, arms 59 must shift in the upright direction when the lower window sash is bodily shifted upon the plane removed from the plane of the upper window sash. Were the molding strip plates 32 rigid with the vertical sash bars 28 of the upper window sash, arms 59 while shifting in an upward direction would encounter said molding strip plates 32 coating with the upper window sash. To obviate the obstacle suitable mechanism is provided for causing said molding strip plates 32 at the upper window sash to shift away from the vertical frame

side members 11, thereby providing clearance between extensions 21 and lips 33 for said arms 59 to shift therewith in their upward shifting movement.

5 The lower corner portions of said lips 33 are filed away as at 62 for permitting entrance of said arms 59 past said lips 33 and extensions 21, at the inception of the upward shifting movement of said arms 59 as they are brought oppositely of the ends of the lower horizontal sash bar 26 of the upper window sash. This contact of arms 59 with the filed away portions 62 of lips 33 will cause molding strip plates 32 at the upper window sash to bodily shift away from the vertical frame side members 11, or more specifically from their contactual engagement with extensions 21. The mechanism for bodily shifting molding strip plates 32 and lips 33 away from weather strips 20 and extension 21, includes transverse slots 63 one adjacent each end of the portion of the molding strip plate 32 which remains in the immediate contact with the inner face of each vertical sash bar 28 of the upper window sash.

20 Washer 64 overlies the body portion of the molding strip plate 32 which is in contact with the inner face of each vertical sash bar 28, including the slot 63. Screw 65 is passed through washer 64 and is driven into the vertical sash bar 28. By virtue of this construction screws 65 constitute guides upon which each molding strip plate 32 is capable of bodily shifting to or away from vertical frame side members 11. For normally maintaining the molding strip plates 32 shifted toward the vertical frame side members 11 with lips 33 normally in a contactual engagement with extensions 21, a pair of resilient wires 66 is provided, one adjacent each end of the portion of each molding strip plate 32 which contacts with the inner face of the vertical sash bar 28. One end of each wire 66 is driven into the vertical sash bar 28, or is otherwise rigidly affixed thereto, as at 67. The opposite end of each wire 66 is soldered or otherwise affixed to the underface of the portion of each molding strip plate 32 which overlies the vertical sash bar 28, as at 68. Normally said wires 66 due to their inherent resilient nature, tend to urge said molding strip plates 32 and their lips 33 toward the vertical frame side members 11 with lips 33 in contactual relation with extensions 21, as best seen in Fig. 6. When however under the actuation of arms 59 as the latter pass past the filed away corners 62 of said lips 33, the latter as well as the molding strip plates 32 are caused to shift away from the vertical frame side members 11 and against the tensioning action of wires 66, thereby shifting said lips 33 away from their contactual relation with extensions 21 effecting a slot between said lips 33 and extensions 21 of a width sufficient for said arms to enter and thereby to permit the unobstructed upright shifting movement of said arms 59 as the lower window sash is bodily shifted upon the plane removed from the plane of the upper window sash.

45 To accommodate said wires 66 the body portions of said vertical sash bars 28 are scooped or hollowed as at 69. In Fig. 1 portions of said molding strip plates 32 are broken away to illustrate depressions 69, wires 66 and the connections of the latter with the vertical sash bars 28 and said molding strip plates 32.

50 When the lower window sash has been moved in a downward direction and away from its alignment on a horizontal plane with the upper window sash, and once said arms 59 have cleared lips 33, the molding strip plates 32, by virtue of the action of wires 66, assume their normal closed position, shifted toward the vertical frame side members 11, with lips 33 in a reestablished contactual closed relation with extensions 21 as seen in Fig. 6.

55 From the hereinabove description it will be apparent that when the lower window sash remains in a horizontal position the upper window sash may be shifted downwardly and oppositely to the lower portion of the window opening, and as far as arms 59 will permit. Thus, either

of the window sashes when in a horizontal position may be shifted in either direction to a predetermined position in order to have a convenient access to wash the outer face of the window pane of either window sash.

Angular shifting of the upper window sash does not require actuation of the molding strip plates 32 and lips 33, since these move with the upper window sash when the same is angularly shifted.

To counterbalance the weight of each sash and thereby to facilitate easy shifting of the two window sashes a pair of springs 70 is provided for the upper window sash, and a pair of springs 71 is provided for the lower window sash. Each spring 70 is disposed intermediately of rods 35 and located within each housing 34. The upper end of each spring 70 is affixed to the upper horizontal frame member 13, as at 72.

Each spring 71 is located forwardly of each inner rod 35, within each housing 34, and substantially intermediately of each inner rod and each molding strip 19. The upper end of each spring 71 is affixed to the upper horizontal frame member 13.

Rigidly affixed to each upper sleeve 39 is bar 73', and rigidly affixed to each of said upper sleeves 47 is bar 74'. Said bars 73' and 74', by their opposite lower ends are at all times in a frictional contract with the lower sleeves 38 and 46, respectively, irrespective as to whether or not upper sleeves 39 and 47 are in contact by their lower ends with the upper ends of the lower sleeves 38 and 46, respectively, as seen in Fig. 4, or whether said upper sleeves are in a spaced relation from said lower sleeves, as is seen in Fig. 5. Said bars 73' and 74' are of a resilient nature for the purpose of exerting a comparatively strong frictional contact upon said lower sleeves 38 and 46, respectively, and consequently for the purpose of engendering friction between said sleeves 38 and the outer pair of rods 35 as well as between said sleeves 46 and the inner rods 35.

Integrally formed with and laterally projecting from each bar 73' and 74' are lugs 73 and 74, respectively, to which the lower ends of springs 70 and 71, respectively, are affixed.

By virtue of the friction aforesaid there is a braking action between sleeves 38 and 46 and their respective outer and inner rods 35. This braking action prevents window sashes from shifting in the upward direction unless manual pressure is imparted to the sashes in order to overcome the said friction and the braking action between the said lower sleeves and rods 35.

In lieu of springs 70 and 71 usual cords may be affixed to lugs 73 and 74 to be actuated by the conventional weights. Whether springs or cords are used, in either event the braking action between the lower sleeves and their coating rods will be maintained for the purpose hereinabove specified.

Latching devices 75 (Fig. 1) are affixed to the upper horizontal sash bar 23 and the lower horizontal sash bar 26, of the lower and upper window sashes, respectively, whereby the two sashes may be locked when the same remain in a closed position within the window opening, as is seen in Fig. 2.

Ring 76 may be affixed to the upper horizontal sash bar 23 of the lower sash whereby said sash may be manually pulled from its closed position shown in Fig. 2 for angularly shifting the same.

Carried by the lower ends of molding strip plates 32 is a pair of spacers 77, best shown in Figs. 1 and 2, which prevent contact of the lower window sash with the upper window sash when the lower window sash has been brought out of the plane of the upper window sash and when the same is upwardly shifted, as is seen in Fig. 7, thereby preventing marring of the two window sashes which would ensue if the sashes were in a frictional contact.

It is also noted that when the lower window sash is in a closed position within the window opening, and in aline-

ment on a vertical plane with the upper window sash, position best shown in Fig. 2, extension 53, with plates 49 and 51, will remain in an outwardly shifted position with relation to the dwelling, thereby causing pins 58 to remain within the closed end of recess 54 as is seen in Fig. 8.

As was already mentioned arms 59, shifting upon their pivots 61 in either direction, that is in the direction inwardly of the dwelling as well as in the direction outwardly therefrom, in conjunction with the action of pins 58 and recesses 54, permit the lower window sash to be shifted to the closed position within the window opening and in a vertical alinement with the upper window sash, position shown in Fig. 2.

From the hereinabove description it will be apparent that said links 56 and pins 58, in conjunction with extensions 53 and recesses 54, define a flexible hinge connection between the lower window sash and the lower sleeves 46, permitting said lower window sash to alternately assume a closed co-planar relation with the upper window sash, as is shown in Fig. 2, or an outwardly shifted position upon a plane removed from the common vertical plane with the upper window sash, as is seen in Fig. 7.

From the hereinabove description it will also be apparent that in addition to the function of bars 73' and 74' already described, the said bars bearing against the lower sleeves 38 and 46, respectively, tend to prevent the downward sliding movement of the upper sleeves 39 and 47, respectively, toward the cooperating lower sleeves 38 and 46, respectively, and thereby tend to maintain one or the other window sash in its angularly adjusted position, indicated by dotted lines in Fig. 4, or by full lines shown in Fig. 8. Such angularly adjusted position of the window sash will be maintained by the action of one or the other of the said bars 73' and 74' until manual pressure is applied against the window sash to alter its angular position against the action of either of the said bars 73' and 74'. Thus, said bars 73' and 74' have a double function, namely, they counteract the action of springs 70 and 71 to maintain the sashes in their vertical adjusted position within the window, and secondly, they maintain the window sashes in their angularly adjusted position within the window, other than the horizontal position, because in that latter position the sashes are maintained by virtue of the upper sleeves having come in contact with the lower sleeves.

While there are described herein preferred embodiments of the present invention, it is nevertheless to be understood that minor changes may be made therein without departing from the spirit and scope of the invention as claimed.

What I claim as new is:

1. In a window construction including a window frame having an opening, a window sash including a vertical sash bar in said opening, a vertical rod rigidly supported within the window frame in a spaced relation with said vertical sash bar, a lower sleeve mounted upon said rod for upright sliding movement thereon, an upper sleeve mounted upon said rod for upright sliding movement thereon, pivot connecting means between the lower end of said vertical sash bar and said lower sleeve, said window sash being adapted for angular shifting upon said pivot connecting means from vertical to horizontal, and an arm, said arm being pivotally connected by one of its ends to said vertical sash bar intermediate of the ends of the latter, the opposite end of said arm being pivotally connected with said upper sleeve, when said window sash has been brought to an angularly shifted position other than the horizontal position said sleeves remaining in a mutually spaced relation, when said window sash has been brought to a horizontal position the lower end of said upper sleeve being capable of shifting in contact with the upper end of said lower sleeve for preventing further angular shifting of said window sash.

2. In a window construction including a window frame having an opening, a window sash including a vertical sash bar in said opening, a vertical rod rigidly supported within the window frame in a spaced relation with said vertical sash bar, a lower sleeve mounted upon said rod for upright sliding movement thereon, an upper sleeve mounted upon said rod for upright sliding movement thereon, pivot connecting means between the lower end of said vertical sash bar and said lower sleeve, said window sash being adapted for angular shifting upon said pivot connecting means from vertical to horizontal, an arm, a pivot connection between one end of said arm and a point upon said vertical sash bar intermediately of the ends of the latter, and a pivot connection between the opposite end of said arm and a point upon said upper sleeve intermediately of the ends of the latter, when said window sash has been brought to an angularly shifted position other than the horizontal position said sleeves remaining in a mutually spaced relation, both of said pivot connections being upon such points with relation to said vertical sash bar and both of said sleeves so as to permit the lower end of said upper sleeve to come in contact with the upper end of said lower sleeve for thereby limiting further angular shifting movement of said window sash beyond the horizontal position of the latter.

3. In a window construction including a window frame having an opening, a window sash including a vertical sash bar in said opening, a vertical rod rigidly supported within the window frame in a spaced relation with said vertical sash bar, a lower sleeve mounted upon said rod for upright sliding movement thereon, an upper sleeve mounted upon said rod for upright sliding movement thereon, pivot connecting means between the lower end of said vertical sash bar and said lower sleeve, said window sash being adapted for angular shifting upon said pivot connecting means from vertical to horizontal, an arm, a pivot connection between one end of said arm and a point upon said vertical sash bar intermediately of the ends of the latter, and a pivot connection between the opposite end of said arm and a point upon said upper sleeve intermediately of the ends of the latter, when said window sash has been brought to an angularly shifted position other than the horizontal position said sleeves remaining in a mutually spaced relation, both of said pivot connections being upon such points with relation to said vertical sash bar and both of said sleeves so as to permit the lower end of said upper sleeve to come in contact with the upper end of said lower sleeve for thereby limiting further angular shifting movement of said window sash beyond the horizontal position of the latter, said rod and said sleeves defining a means for upright shifting movement of said window sash irrespective of its angular shifted position.

4. In a window construction including a window frame having an opening, a pair of window sashes in said opening, said window sashes being adapted to assume a common vertical plane when they remain in a closed position, a vertical rod supported within the window frame in a spaced relation with one of said window sashes, a sleeve positioned upon said rod for an upright shifting movement thereon, said last named window sash including a vertical sash bar, a plate mounted upon the side edge of said vertical sash bar, a portion of said vertical sash bar being reduced for defining a recess between said vertical sash bar and said plate, a link pivoted by one of its ends to said plate, said link being positioned adjacent the inner face of said plate and being adapted for angular swinging movement upon its pivot to or out of said recess, said plate being provided with a transverse slot opening upon one edge of said plate, a second sleeve positioned upon said rod for an upright sliding movement thereon, pivotal connecting means between said vertical sash bar and second sleeve, and a horizontal pin

affixed by one of its ends to said first named sleeve, said pin being positioned oppositely of said slot and being adapted to fall in or extend out of said slot through the open end of the latter, the opposite end of said pin being pivotally connected with the opposite end of said link, said last named window sash being capable of bodily shifting out of said common vertical plane to assume a position upon a plane in parallelism with said common vertical plane, when said last named window sash remains upon said common vertical plane said pin remaining within the closed end of said slot, when said last named window sash has been shifted out of the said common vertical plane said link being adapted for angular shifting out of said recess and said pin being adapted to shift out of said slot through the open end of the latter for supporting said last named window sash upon the newly established plane out of said common vertical plane, while in that newly established plane said last named window sash being adapted for an upright shifting movement being guided in that movement by said sleeves and said rod.

5. In a window construction including a window frame having an opening, a window sash in said opening, a vertical rod rigidly supported within the window frame in a spaced relation with said window sash, a lower sleeve, an upper sleeve, said sleeves being set upon said rod for an upright shifting movement thereon, said window sash being connected with said lower sleeve, a bar rigidly affixed by its upper end to said upper sleeve, and means engaging the lower end of said bar for counterbalancing the weight of said window sash for facilitating the upright shifting movement thereof within the window frame, the lower end of said bar being in contact with the side of said lower sleeve for exerting a contactual pressure upon said lower sleeve for effecting friction therebetween and said rod for rendering said means inoperative and thereby for maintaining said window sash in its upwardly shifted adjusted position within the window against the action of said means.

6. In a window construction including a window frame having an opening, a window sash in said opening, a vertical rod rigidly supported within the window frame in a spaced relation with said window sash, a lower sleeve, an upper sleeve, said sleeves being set upon said rod for an upright shifting movement thereon, said window sash being connected with said lower sleeve, a bar rigidly affixed by its upper end to said upper sleeve, a lug laterally projecting from the lower end of said bar, and means engaging said lug for counterbalancing the weight of said window sash for facilitating the upright shifting movement thereof within the window, the lower end of said bar being in contact with the side of said lower sleeve, said bar being of a resilient nature for exerting a contactual pressure upon said lower sleeve for effecting friction therebetween and said rod for rendering said means inoperative and thereby for maintaining said window sash in its upwardly shifted adjusted position within the window against the action of said means, said sleeves guiding the upright shifting movement of said window sash.

7. In a window construction, including a frame having an opening, said frame including an upper horizontal frame member, a window sash in said opening, a vertical rod rigidly supported within the window frame in a spaced relation with said window sash, a lower sleeve, an upper sleeve, said sleeves being set upon said rod for an upright shifting movement thereon, said window sash being connected with said lower sleeve, a bar rigidly affixed by its upper end to said upper sleeve, a lug laterally projecting from the lower end of said bar, and a coil spring affixed by one of its ends to said upper horizontal frame member and by its lower end to said lug, said coil spring counterbalancing the weight of said window sash for facilitating the upright shifting movement thereof within the window opening, the lower end of said bar

being in contact with the side of said lower sleeve; said bar being of a resilient nature for exerting a contactual pressure upon said lower sleeve for effecting friction therebetween; and said rod for counteracting the action of said coil spring upon said window sash for maintaining the latter in its upwardly shifted adjusted position, said sleeves guiding the upright shifting movement of said window sash.

8. In a window construction, including a frame having an opening, a window sash in said opening, a vertical rod rigidly supported within the window frame in a spaced relation with said window sash, a lower sleeve, an upper sleeve, said sleeves being set upon said rod for an upright shifting movement thereon, a pivot connection between said window sash and said lower sleeve, an arm pivotally connected by one of its ends to said upper sleeve, the opposite end of said arm being pivotally connected to said window sash in a spaced relation with said pivot connection; said window sash being adapted for angular shifting movement upon said pivot connection, said arm facilitating angular adjustment of said window sash; said upper sleeve being actuated by said arm to shift the former to or away from said lower sleeve during the angular shifting movement of said window sash, and a bar rigidly affixed by its upper end to said upper sleeve, the lower end of said bar being in contact with the side of said lower sleeve for bearing thereagainst for engendering friction between said lower sleeve and said rod for maintaining said sleeves in their spaced relation and thereby for maintaining said window sash in its angularly adjusted position within the window frame.

9. In a window construction including a window frame having an opening, a pair of window sashes in said opening, said window sashes being adapted to assume a common vertical plane when they remain in a closed position, a vertical rod supported within the window frame in a spaced relation with one of said window sashes, a sleeve positioned upon said rod for an upright shifting movement thereon, said last named window sash including a vertical sash bar; a plate mounted upon the side edge of said vertical sash bar, a portion of said vertical sash bar being reduced for defining a recess between said vertical sash bar and said plate, a link pivoted by one of its ends to said plate, said link being positioned adjacent the inner face of said plate and being adapted for angular swinging movement upon its pivot to or out of said recess, said plate being provided with a transverse slot opening upon one edge of said plate, a second sleeve positioned upon said rod for an upright shifting movement thereon, said second sleeve being capable of an upright shifting movement upon said rod independently of the upright shifting movement thereon of said first named sleeve, a horizontal pin affixed by one of its ends to said first named sleeve, said pin being positioned oppositely of said slot and being adapted to fall in or extend out of said slot through the open end of the latter, the opposite end of said pin being pivotally connected with the opposite end of said link, said last named window sash being capable of bodily shifting out of said common vertical plane to assume a position upon a plane in parallelism with said common vertical plane, when said last named window sash remains upon said common vertical plane said pin remaining within the closed end of said slot, when said last named window sash has been shifted out of the said common vertical plane said link being adapted for angular shifting out of said recess and said pin being adapted to shift out of said slot through the open end of the latter, and an arm pivotally connected by one of its end with said vertical sash bar at a point in a spaced relation with said link, by the opposite end said arm being pivotally connected with said first named sleeve, said arm

coacting with said link and said pin for supporting said last named window sash upon the newly established plane out of said common vertical plane, while in that newly established plane said last named window sash being adapted for an upright shifting movement being guided in that movement by said sleeves and said rod.

10. In a window construction including a window frame having an opening, a pair of window sashes in said opening, said window sashes being adapted to assume a common vertical plane when they remain in a closed position, a vertical rod supported within the window frame in a spaced relation with one of said window sashes, a sleeve positioned upon said rod for an upright shifting movement thereon, said last named window sash including a vertical sash bar, a plate mounted upon the side edge of said vertical sash bar, a portion of said vertical sash bar being reduced for defining a recess between said vertical sash bar and said plate, a link pivoted by one of its ends to said plate, said link being positioned adjacent the inner face of said plate and being adapted for angular swinging movement upon its pivot to or out of said recess, said plate being provided with a transverse slot opening upon one edge of said plate, a second sleeve positioned upon said rod for an upright shifting movement thereon, said second sleeve being capable of an upright shifting movement upon said rod independently of the upright shifting movement thereon of said first named sleeve, a horizontal pin affixed by one of its ends to said first named sleeve, said pin being positioned oppositely of said slot and being adapted to fall in or extend out of said slot through the open end of the latter, the opposite end of said pin being pivotally connected with the opposite end of said link, said last named window sash being capable of bodily shifting out of said common vertical plane to assume a position upon a plane in parallelism with said common vertical plane, when said last named window sash remains upon said common vertical plane said pin remaining within the closed end of said slot, when said last named window sash has been shifted out of the said common vertical plane said link being adapted for angular shifting out of said recess and said pin being adapted to shift out of said slot through the open end of the latter, and an arm pivotally connected by one of its ends with said vertical sash bar at a point in a spaced relation with said link, by the opposite end said arm being pivotally connected with said first named sleeve, when said link has shifted out of said recess and said pin has shifted out of said slot said arm being capable of assuming an angular position on a transverse plane with relation to said last named window sash for supporting in conjunction with said link and said pin the said last named window sash upon the newly established plane out of said common vertical plane, while in that newly established plane said last named window sash being adapted for an upright shifting movement being guided in that movement by said sleeves and said rod.
